US00D868973S

(12) **United States Design Patent** (10) Patent No.: **US D868,973 S**
Lin (45) Date of Patent: ** Dec. 3, 2019

(54) **PART OF THE GENERATOR FOR
OXYHYDROGEN GAS**

(71) Applicant: **Hsin Yung Lin**, Shanghai (TW)

(72) Inventor: **Hsin Yung Lin**, Shanghai (TW)

(**) Term: **15 Years**

(21) Appl. No.: **29/591,193**

(22) Filed: **Jan. 17, 2017**

(30) **Foreign Application Priority Data**

May 16, 2016 (TW) 105302692

(51) LOC (12) Cl. **24-02**

(52) U.S. Cl.

USPC **D24/164**

(57) **CLAIM**

The ornamental design for a part of the generator for oxyhydrogen gas, as shown and described.

DESCRIPTION

FIG. 1 is a perspective view of a part of the generator for oxyhydrogen gas according to the invention;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is another perspective view thereof; and,

FIG. 10 is another perspective view thereof.

In the drawings, the broken lines are for the purpose of illustrating environment only and form no part of the claimed design.
